(57) **CLAIM**

The ornamental design for a floating solar panel, as shown and described.

DESCRIPTION

Fig. 1.1 is a top perspective view of a floating solar panel; Fig. 1.2 is a bottom perspective view of a floating solar panel;

Fig. 1.3 is a top plan view of a floating solar panel;

Fig. 1.4 is a bottom plan view of a floating solar panel;

Fig. 1.5 is a front plan view of a floating solar panel; and

Fig. 1.6 is a side plan view of a floating solar panel.
